UNITED STATES PATENT OFFICE.

EDWARD B. HESS AND LEWIS C. MYERS, OF BROOKLYN, NEW YORK, ASSIGNEES TO
ROYAL TYPEWRITER COMPANY, INC., OF NEW YORK, N. Y., A CORPORATION OF
NEW YORK.

TYPE-WRITING MACHINE.

1,212,947.

Specification of Letters Patent. Patented Jan. 16, 1917.

Original application filed May 3, 1915, Serial No. 25,384. Divided and this application filed April 14, 1916.
Serial No. 91,060.

To all whom it may concern:

Be it known that we, EDWARD B. HESS and LEWIS C. MYERS, of the borough of Brooklyn, county of Kings, and State of New York, citizens of the United States of America, have jointly invented certain new and useful Improvements in Type-Writing Machines, of which the following is a specification.

This invention relates to typewriting machines of the class in which the key levers and type bars are held in normal substantially horizontal positions by springs operatively connected therewith, and it consists in novel means hereinafter described whereby the springs may be simultaneously adjusted to vary their tension. This mechanism preferably comprises a frame mounted to rock in suitable bearings extending from the rear portion of the machine frame, which carries at its upper end a vertically adjustable plate to which the springs are attached and which is provided at its lower end with means for adjusting its position in such manner as to simultaneously change the lengths of the springs and thereby vary the tension applied to the key levers.

Figure 1 is a central section of the machine, looking toward the left; Fig. 2 is a perspective view of an adjustable rocking frame or plate to which one end of each spring of the type bar is attached, and Fig. 3 is a plan view of the lower part of the rear end of the machine frame and the rocking frame.

The parts of a Royal typewriter shown to illustrate the application of the features of this invention thereto may be briefly stated as consisting of the main frame 6, carriage 7, carriage shift 8, platen 9, spacing lever 10, paper pan 11, type bars 12, type head rest 13, universal bar 14, ribbon spool cover or housing 15, top casing and dust guard 16.

The key levers 17 are each connected by a vertical link 18 to a front link 19 connected at the rear end to type bar 12 by a link 20. To link 20 is secured a bar or link 21 having the rear end bent to engage the universal bar 14. On each universal bar connecting link 21 is a spring 22 whose rear end connects with an adjustable rocking frame 23, as and for the purpose hereafter described.

The inner ends of the key levers are piv-

totally supported on a bearing bar or comb bar 25 extending across the machine.

The supporting bar 30 carrying the bearings of the front links 19 has a flange 31 at its inner or rear side to protect the bearings from dirt from the inner part of the machine, the links being bent, as shown, to extend down under the flange 31 and beneath the type head rest 13. The upper side of the bar 30 is sloped downwardly toward the front and above it is secured a dust guard or shed 32, whose upper part is laterally curved to conform to the curvilinear arrangement of the type heads, to afford free access for cleaning the type and its front part 33 extends downwardly to the key board, acting as a protecting apron for the front of the machine.

The frame 23 for the type bar springs 22 is held between lugs 34 extending inwardly from the back wall of the frame 6, and is free to rock on studs 35 which pass through said lugs. A set screw 36 fitted in a boss 37 at the central lower part of the frame 23 abuts against the back wall of the frame 6, and by it the upper end of the frame to which the springs 22 are attached may be adjusted to vary the tension of the springs collectively. It is sometimes found that springs of the character of 22 are apt, from irregularities in the universal bar links 21 or in assembling them, to interfere with the upturned ends of the links. To provide against this an angular spring plate 38, to the horizontal part of which the springs 22 connect, is by its vertical member secured by screws 39 to the upper part of the frame 23. These screws pass through slots 40 in the plate thereby providing ready vertical simultaneous adjustment of all the rear ends of the springs so as to avoid all interference of the springs with the links 21 and drag on the universal bar due thereto.

41 indicates a line lock blade and 42 a small curved arm attached thereto near the end and extending rearwardly. This rocker arm acts against a portion of the frame to limit the movement of the upper end of the line lock blade so as to avoid unpleasant noise due to the blade striking the comb or bearing bar in which the key levers are guided.

It will be observed that the springs 22

hold the key levers in their normal position and that when the frame 23 is moved the length of the springs is adjusted and the tension applied to the key levers is changed. 5 The springs 22, type bars 12, and key levers 17 are all disposed in substantially horizontal planes and the links 19 and 20 are similarly disposed, thus affording a minimum strain, which is a tensile one, to the operation 10 of the springs. It will also be observed that each link 18 is connected with a link 19 near its flexing connection with a link 20. These features are of importance in the operation of a machine embodying 15 our present improvements.

The application for this patent is a division of our application No. 25,384, filed May 3, 1915. The annexed drawings show certain features of invention relating particularly 20 to the bearing bar for the bearing ends of key levers and an alining and guard plate associated therewith. No claims are made herein to this subject matter, as claims to these features are made in our original application 25 for patent above mentioned.

We claim:

1. In a typewriting machine, the combination with the type bars and the universal bar to which they are connected of an upright frame pivotally supported between its upper and lower ends, a plate attached to and vertically adjustable on said frame, springs connecting the type bars with said plate and tending to pull the upper part of 30

the plate forwardly and means carried by the lower portion of said frame for limiting its movement.

2. In a typewriting machine, the combination with the type bars and a universal bar to which they are connected, of an upright rocking frame pivotally supported between its upper and lower ends within the machine casing, springs connecting the type bars with the upper portion of said rocking frame and tending to pull the upper part 45 thereof forward, and a set screw within the machine casing carried by the lower portion of said rocking frame for limiting its movement.

3. In a typewriting machine, the combination with the type bars and a universal bar to which they are connected, of an upright rocking frame pivotally supported between its upper and lower ends within the machine casing, springs connecting the type 55 bars with the upper portion of said rocking frame and tending to pull it forward, and a set screw extending through the lower portion of said rocking frame and engaging the inner rear wall of the machine casing. 60

In testimony whereof, we have hereunto subscribed our names.

EDWARD B. HESS.
LEWIS C. MYERS.
